United States Patent Office

Des. 210,494

Patented Mar. 12, 1968

210,494

RECORD CHANGER OR SIMILAR ARTICLE

Ralph D. Davis, Stevensville, Mich., assignor to V-M Corporation, Benton Harbor, Mich., a corporation of Michigan

Filed Feb. 14, 1967, Ser. No. 5,805

Term of patent 14 years

(Cl. D56—4)

FIG. 1

FIG. 2

FIG. 3

FIGURE 1 is a perspective view of the top, front and one side of a record changer or similar article showing my new design;

FIGURE 2 is a rear elevational view thereof; and

FIGURE 3 is an elevational view thereof taken from the side opposite that shown in FIGURE 1.

The dominant features of my design for a record changer or similar article reside in the portions shown in full lines.

I claim:

The ornamental design for a record changer or similar article, substantially as shown and described.
